COMBINATION RANGE

Henry Lange, Quincy, Ill., assignor to The Quincy
Stove Manufacturing Company, Quincy, Ill., a
corporation of Illinois

Application March 24, 1930, Serial No. 438,524

2 Claims. (Cl. 126—273)

The present invention relates to improvements in combination ranges and more particularly refers to a combined coal and gas range in which the inconveniences and dangers attendant upon former constructions are largely eliminated, and in which ideal baking conditions will prevail.

Heretofore it has been the practice to construct two-fuel combination range ovens by placing a burner in the bottom of the oven and inserting a baffle plate above the burner to spread the heat from the gas burner in the oven chamber. It proved difficult to obtain ideal baking conditions with this arrangement because it was impossible to establish an even heat circulation, which is essential to ideal oven baking conditions. The arrangement referred to involves a number of dampers, which have to be operated in connection with the gas burner in order to furnish air supply to the burner and for carrying off the gases generated in the oven. Without a provision of this kind it was impossible to establish any circulation, for the reason that the confined heat in the oven, without any outlet, would reflect upon the burning of the gas, causing "floating", which became a source of great danger.

A further objection to the damper arrangement was that quite frequently the operator would neglect to open the vent damper and explosion occurred, which became very annoying to say nothing about the danger of burning the operator of the range. While it is true that most damper arrangements of this kind were created for the very purpose of being fool-proof, nevertheless very few of them worked out in actual practice.

An object of the invention is to correct the deficiencies above referred to and to provide an improved range having adequate oven heat circulation and outlet.

Another object of the invention is to provide, in a combination range, a combined bottom oven burner and overhead broiler burner, so coordinated as to gas supply that only one of the burners may be supplied with fuel at a time.

With the foregoing and other objects in view, the invention will be more fully described hereinafter and more particularly pointed out in the appended claims.

In the drawings, in which like reference numerals refer to like or corresponding parts through the several views.

Figure 1 is a vertical section taken longitudinally through a combination range constructed according to the present invention.

Fig. 2 is a vertical transverse section taken on the line 2—2 in Fig. 1 and

Fig. 3 is a horizontal sectional view taken on the line 3—3, also in Fig. 1.

Referring more particularly to the drawings, 10 designates generally the casing of the improved combination range, having at one end thereof

the firebox 11 disposed above the ashpit 12. These parts will be accompanied by the usual features, such as the grate 13 etc., and above such firebox may be disposed stove lids or plates 14 set in the stove top 15.

In this stove top 15 are also set a number of grills 16 cooperating with gas burners 17 in connection with a suitable source of gas supply and having the usual controlling gas cocks. These gas burners 17 are preferably set off in a compartment 18 separated by a casing 19 from the top flues of the oven 20 which has the usual front door 21 shown in Fig. 2.

Within the oven 20 is disposed a lower or bottom gas burner 22, and an upper or broiler burner 23, these burners also being in connection with an appropriate source of gas supply and having an improved control device as hereinafter more fully referred to.

The stove bottom is indicated at 24 and the oven bottom at 25, being spaced above the stove bottom 24 to provide the bottom horizontal flues 26 and 27 disposed at opposite sides of the partition or baffle 28. For convenience in illustration, particularly of Figs. 1 and 2, this baffle plate 28 is shown as extended in front of the burner stem 29 but as a matter of practice, the partition will preferably terminate at or about said burner stem 29 in order to provide adequate sweep of the warm air and heated products from one flue 26 to the opposite flue 27 at the forward part of the stove.

Now the oven bottom 25 is preferably supported upon ledges 30 carried by one end wall 10 of the stove and an intermediate separating wall 31 disposed between the oven and the firebox 11 and ashpit 12. Upon the ledges 30 are also supported inverted U-shaped or channel spacing members 32, which cooperate with the lugs 33 upstanding from the oven bottom 25 to receive therebetween the lower edges of the oven liner plate 34. These plates 34 may be made from sheet iron or other desired material and they are spaced from the walls 10 and 31 whereby to provide passages or flues 35 between these parts, which passages are open at their upper ends into the head space of the oven 20. The liner plates 34 are corrugated or otherwise formed to provide ledges 36 for selectively receiving the baffle plate 37 having the marginal openings 38 therein.

In the top plate or oven roof 39 at one side, namely at the side adjacent the firebox 11 are provided openings 40, placing the oven base in communication with a substantially horizontal and transversely extending flue 41 opening at the rear of the stove unobstructedly to the stack as indicated in Fig. 3. This flue 41 may have the triangular cross section shown in Fig. 1, such flue being comprised between the perforated portion of the oven top 39, the extended upper portion 42

of the vertical partition wall 31 and a plate 43 which extends diagonally across from the upper end of the wall 42 to the oven roof 39 adjacent the openings 40.

5 The stack connection is shown at 44 in Figs. 2 and 3 and as before stated the flue 41 opens directly to this stack connection 44 and is in communication with the same at all times irrespective of the action of the damper 45, which is 10 intended to control the flow of the heated products from the firebox 11 to and through the oven flues or directly to the stack connection 44.

The upper portion of the firebox 11 communicates, through an opening 46, with the upper 15 flues 47 and 48 between the oven roof 39 and the casing 19. These flues 47 and 48 may be disposed side by side or the flue 47 may be stepped above the flue 48. The damper 45 closes the rear end of the flue 47, or when open, permits the direct 20 outflow of the heated products from the firebox 11 to the stack connection 44.

As shown in Fig. 3, the horizontal oven flue 48 communicates at its rear end with the down-take flue 49, and this down-take flue connects at its 25 lower end with the rear end of the lower horizontal oven flue 26. The rear end of the other lower horizontal oven flue 27 communicates with the lower end of the up-take flue 50, which, as shown in Fig. 3, is separated from the down-take flue 49 by a partition 51. The rear wall of the oven is 30 shown at 52 in Fig. 2 as being spaced from the outer stove rear wall 53. The vertical flues 49 and 50 are provided between these walls 52 and 53. The vertical partition 51 may be a continuation 35 of the horizontal partition 28, if desired.

As shown in Fig. 3, one end of the damper 45 is provided with a trunnion 54 journaled in an opening in the partition plate 51. The damper 45 is provided with a crank 55 inserted through 40 an opening in the damper operating bar 56 which projects up through the stove top 15 and is accessible for operation above the stove.

In Fig. 1 the broiler burner 23 and the lower burner 22 are shown as supplied with gas through 45 branch pipes 57 and 58 having connection with a feeder pipe 59 from the manifold 60. Where the feeder pipe 59 joins with the branch pipes 57 and 58 is located a three-way cock 61 which will operate to shut off the gas from both burners 22 and 23 or to supply the gas to one or the other burner but not to both burners at the same time.

In the operation of the stove, the articles to be baked may be placed upon the baffle plate 37 and this baffle plate may be placed at various 55 elevations in the oven, the same being slidable in and out on the ledges 36 provided by the liner plates 34. In this way the article to be baked may be placed in a proper location relative to the burners 22 and 23. The heat rising from the lower burner 22 will be intercepted by the baffle plate 37 and deflected laterally of the baffle plate 37. This deflected heat will partially pass through the openings 38 in the baffle plate which is spaced above the base of the oven and partially 60 through openings 62 in the lower portions of the liner plates 34 and into the air spaces 35 provided between the liner plates and the outer walls 10 and 31, by which the heat will also ascend into the head space of the oven; whence it may seek exit out through the openings 40 in the oven roof 39 and into the horizontal flue 41. As heretofore explained the flue 41 will carry the gases 65 and heat unobstructedly to the stack connection

44 at the rear of the stove. In this way I obtain an adequate circulation of heat within the oven and an adequate yet restricted outlet of the same, whereby to maintain proper oven temperature but at the same time avoid the dangers 80 incident to prior construction. The openings 40 and flue 41 afford a ventilating system which will carry off the fumes from the oven to the smoke pipe outlet. This flue 41 has the advantage of doing away with any burner arrangement, is always open, will create a perfect circulation of heat in the oven and will be free from soot from the coal fire, because it is in no way connected with the coal flues of the range.

The three-way cock 61 is a factor of safety, 90 feeding as it does both the broiler and oven burners 23 and 22, but this gas cock will not permit the use of top and bottom burners at the same time.

Where the coal fire is used, the heat will flow 95 out from the firebox through the opening 46 and into the top oven flue 47, thence into the companion top oven flue 48, down the vertical flue 49 to a point below the oven bottom 25, thence forwardly through the lower oven flue 26 and in 100 front of the partition or baffle 28, into the opposite lower oven flue 27, by which the heat and hot products are carried rearwardly to the other vertical flue 50. This flue 50 communicates back of the damper 45 with the stack connection 44. 105 When the damper 45 is open, the heat and products of combustion from the firebox 11 will flow out directly from the flue 47 into the stack connection 44. By this means adequate oven temperature control is had.

Having thus described the invention, what is 110 claimed as new is:

1. In an oven having bottom, side and top walls, vertically disposed liner plates resting on said bottom wall within said oven and spaced from opposite side walls thereof to form vertical flues between said plates and said walls, said liner plates having openings extending therethrough adjacent the lower ends thereof, a baffle plate disposed between said liner plates above 115 said openings and having openings extending therethrough adjacent said liner plates, a gas burner disposed in the lower portion of said oven in spaced relationship to said baffle plate, said baffle plate being exposed to the flame of the burner, and a flue for drawing off the gases from the upper portion of said oven above said baffle plate to promote an even circulation of heated air in the oven.

2. In an oven having bottom, side and top 120 walls, vertical parallel liner plates resting on said bottom wall and disposed in spaced relation to opposite side walls of said oven to provide vertical unobstructed flues between said plates and walls, said plates having openings extending therethrough adjacent the lower ends thereof, a vertically adjustable horizontal baffle plate supported 125 between said liner plates above the openings therein, said baffle plate having openings extending therethrough adjacent the ends thereof, a gas burner disposed in the lower portion of said oven in spaced relationship to said baffle plate, said baffle plate being exposed to the flame of the burner, and a flue connection for drawing off the gases from the upper portion of said oven above 130 said flues and baffle plate whereby to induce an even circulation of heated air within said oven.

HENRY LANGE.
